UNITED STATES PATENT OFFICE.

MINOR F. H. GOUVERNEUR, OF VICTOR, NEW YORK, ASSIGNOR TO LOCKE INSULATOR CORPORATION, OF BALTIMORE, MARYLAND, A CORPORATION OF MARYLAND.

INSULATOR.

Application filed April 7, 1921. Serial No. 459,312.

The invention relates to insulators for high tension power transmission, and more particularly to the general class of suspension or strain insulators. The principal object of my invention, broadly stated, is to improve the construction of insulators of the suspension or strain type in such manner that the electrical and mechanical efficiency of the dielectric body portion of the insulator is greatly increased.

To this end I provide an insulating body portion of dielectric material having spaced interlinking passages therein, the said body portion being so constructed that the thickness of the dielectric material adjacent the passages is substantially constant at all points.

Another object of the invention is to provide a simple and easily manufactured form of disk insulator in which the interlinking passages thereof are located so that the least distance between the conductors of opposite potential extending through the said passages is equal to the distance between surfaces of opposite potential throughout the portion of the insulating or dielectric body in the neighborhood of the passages.

Another object of the invention is to provide an insulator of dielectric material with substantially semicircular interlinking passages therein and to construct the insulator so that the mechanical strain is transmitted to the body of material as a direct compression without unequal distribution of the electrical stresses over the surfaces of opposite potential.

A primary feature of my invention consists in providing the opposite faces of an insulator body with projections whose surfaces are surfaces of revolution (or substantially so) generated by rotating a curved line, preferably an arc of a circle, about an axis which extends parallel to the plane of said arc and which lies without the circle of said arc or generatrix. The said projections therefore are of toroidal form, being segments of a torus.

Another principal feature of the invention resides in forming the body of dielectric material with interlinked passages, and with a plurality of elongated projections disposed upon opposite sides of said body parallel with the respective passages and crossing each other.

There are other features of invention as will hereinafter more fully appear from

the detailed description of the single embodiment thereof which has been illustrated in the drawings, the novel features of the invention being pointed out in the claims.

In the drawings,

Figure 1 is a top plan view of a disk insulator of the suspension or strain type constructed in accordance with my invention.

Figure 2 is a transverse vertical sectional view of the insulator, the section being taken in the plane of the line 2-2 of Fig. 1; and

Figure 3 is also a transverse vertical sectional view of the insulator, the section being taken on the plane of the line 3-3 of Fig. 1.

Throughout the specification and drawings like parts are designated by like reference characters.

The insulator preferably comprises a disk-shaped dielectric body portion 1, which is conveniently provided adjacent its peripheral edge 2 and on the lower face 3 thereof with a downwardly extending skirt or flange portion 4. If desired the outer face of the flange 4 may be formed with a circumferential groove or undercut portion 5 the purpose of which is to reduce the thickness of the insulator adjacent its edge and to increase the flash-over distance between terminals of opposite potentials.

The upper face 6 of the disk 1 is furnished with a toroidal projection 7 and a correspondingly shaped projection 8 is also formed upon the lower face 3 of the disk. The projections 7 and 8 are substantially elliptical in plan and are preferably arranged, in the type of insulator here illustrated, centrally of the disk 1 with their major axes crossing each other at an angle.

Passing lengthwise through the projections 7 and 8 are curved passages or channels 9 and 10, respectively, the said channels being adapted to receive the supporting members or metallic elements by which the insulators are connected to the supports, or to companion insulators, or to the conductor. The said passages 9 and 10 interlink within the body of the insulator and are separated by intervening dielectric material where they cross or intersect.

The passage 10 preferably follows the arc of a circle whose center of curvature lies in the locus of the center of symmetry of the generatrix of the toroidal projection 7, and whose radial distance from said center of

symmetry is equal to the radius of the said generatrix. The passage 9 and the toroidal projection 8 are similarly related, the passages 9 and 10 thus following the loci or paths of the respective centers of symmetry of the generatrices of the corresponding projections 7 and 8. By this construction the ends of the respective passages 9 and 10 which open to the opposite faces 3 and 6 of the insulator, merge with or are tangent to the sides of their respective projections, and said passages extend in curves respectively concentric with the surfaces of the corresponding projections.

15 The cross sectional dimensions of the passages 9 and 10 are such that the thickness of the walls by which the said passages are surrounded is equal to that of the neighboring parts of the disk. The dielectric thickness between surfaces of opposite potential is thus rendered constant and localization or concentration of electrical stress along a line between the conductors or terminals is therefore obviated. This effects a considerable increase in the puncture value of the insulator. Not only is the electrical efficiency of the insulator increased by the avoidance of adjacent thick and thin sections of the dielectric material, but an insulator embodying my invention is simpler and cheaper to manufacture, since the absence of thick sections of the insulator body adjacent thinner sections obviates the tendency, during drying, to produce cracks or other imperfections at the junctures of sections of unequal thickness.

20 The insulator may, if desired, be cast with the passages 9 and 10 therein, but it is preferred to mold or pug the insulators. When made by the molding process the passages 9 and 10 for the conductors are cut or formed in the insulator body when the same is in a plastic state, these passages being preferably produced in the manner described in my co-pending application, Serial No. 384,388, filed May 26, 1920. By forming the passages 9 and 10 in the insulator prior to its hardening all substantial inequalities in thickness are removed, and consequently the liability to produce cracks or similar imperfections in the insulator is minimized. The insulator may, therefore, be molded from a dense porcelain mix, whereas if cast or allowed to dry prior to forming the passages 9 and 10 therein an open and porous porcelain mix would be required.

adjacent portions of the respective projections.

2. An insulator comprising a disk of dielectric material having interlinking circular passages therein, the open ends of the respective passages being disposed on opposite faces of said disk, and projections on the opposite sides of said disk each of which extends between the open ends of one of the said passages.

3. An insulator comprising a disk of dielectric material each face of which is perforated by openings leading to a separate circular passage, said passages being interlinked in the body of said disk, and the dielectric thickness of said disk at all points adjacent said passages being substantially constant.

4. An insulator comprising a disk of dielectric material having on its opposite faces toroidal projections, and provided with curved interlinked passages entering said disk from the opposite faces thereof, the ends of the respective passages being substantially tangent to the adjacent projections, whereby the dielectric thickness of said disk at all points adjacent the said projections is substantially constant.

5. An insulator comprising a body portion of dielectric material provided with interlinked passages and with a plurality of projections disposed upon opposite sides of said body and crossing each other.

6. An insulator comprising a body portion of dielectric material provided with interlinked passages and with a plurality of elongated projections upon opposite sides of said body, each of said projections being disposed with its major dimension lying in the plane of a corresponding one of said passages.

7. An insulator comprising a disk of dielectric material having a curved passage opening at its ends on one side of said disk, and provided on its opposite side with a projection whose exterior is a surface of revolution, the generatrix of said surface of revolution being a circular curve the locus of whose center of curvature is in said passage, and the axis of revolution of said surface passing through the center of curvature of said passage.

8. An insulator having a body portion of dielectric material provided with a plurality of passages and with a plurality of projections respectively corresponding to said passages, the line of intersection of the surface of each of said projections with the plane of the corresponding passage being parallel to said last named passage and the intersection of said surface with planes normal to said last named passage being spaced equally from said last named passage.

In testimony whereof I affix my signature.

MINOR F. H. GOUVERNEUR.
